UNITED STATES PATENT OFFICE.

FRANZ REITER, OF BERLIN-CHARLOTTENBURG, GERMANY, ASSIGNOR TO WESTINGHOUSE ELECTRIC AND MANUFACTURING COMPANY, A CORPORATION OF PENNSYLVANIA.

INSULATOR.

Application filed November 14, 1925, Serial No. 69,054, and in Germany January 28, 1925.

My invention relates to insulators and particularly to terminal means therefor.

One object of my invention is to provide an insulator that shall be free of damage 5 caused by expansion forces between its conducting and dielectric parts.

Another object of my invention is to provide an insulator terminal structure in which a member that has hitherto been considered 10 necessarily of several parts shall be constructed as a single integral member.

A further object of my invention is to provide an insulator that shall be simple and durable in construction, economical to manufacture and effective in its operation.

In an insulator of a certain type, in which the dielectric body is provided with a cylindrical projection having an enlarged head or outer end, it has been usual to provide a 20 terminal structure comprising a halved metal ring disposed around the cylindrical dielectric portion and screwed or riveted together at the adjacent ends of its component halves.

In such a structure, where rivets are employed or where screws become rusty, the terminal member is difficult to remove. Also, where the screws are tightened too much during cold weather, they may be fractured when a rise of temperature occurs. It is my 30 aim to provide an insulator that shall overcome the above-mentioned objections and that shall not only comprise fewer and simpler parts but that shall be easier to assemble.

Accordingly, in practicing my invention, 35 I provide an insulator of the above indicated character and a terminal structure therefor that permit the use of a ring member constituting a single integral element in such combination with other parts as to overcome the above mentioned objections and to 40 provide a materially improved insulator.

Figure 1 of the accompanying drawings is a side view, partially in elevation and partially in section along the line I—I of Fig. 2, 45 of the upper or terminal portion of an insulator embodying my invention.

Fig. 2 is a plan view of the device shown in Fig. 1.

Figs. 3 and 4 are detail views taken along 50 the lines III—III and IV—IV, respectively, of Fig. 2, and

Fig. 5 is a detail view of a portion of the device shown in the other figures, taken along a horizontal section as indicated by line V—V in Fig. 4.

The device comprises, in general a dielectric body member having a petticoat portion 1, only a portion of which is shown, a cylindrical terminal portion 2 projecting from the body member, and a laterally-projecting portion or flange 3 adjacent to the outer end of the cylindrical portion 2. A terminal structure 4, in the form of a composite ring, surrounds the cylindrical portion 2 between the laterally-projecting portions 1 and 3.

The composite ring structure 4 comprises a relatively thin cushioning ring or member 6 next adjacent to the cylindrical dielectric portion 2. The member 6 may be of any suitable material formed as two half 70 rings but, since it is preferably of pliable material such as lead, may be formed as a nearly whole or single integral ring having but one perimetral slot whereby it may be distended laterally and placed around the portion 2 from the side thereof. A halved ring or spacer element 7 closely fits in position around the cushioning ring 6 and has its outer cylindrical surface of a diameter substantially equal to, or slightly greater 75 than, the diameter of the dielectric flange 3.

An outer ring 8, constituting a single integral element, is of such shape and size as to freely pass over the flange 3 into closely fitting position around the spacer ring 7 and is provided with laterally-projecting means or hooks 9 for supporting suspension cables 10. Enlarged or reinforcing portions 11 having longitudinal recesses 12 therein are provided on the outer perimeter of the ring 8 at diametrically opposite positions substantially 80 right-angularly related to the hooks 9.

The recesses 12 provide spaces between the rings 7 and 8 for the reception of means, such as pliable metal members 14, for holding 95 the rings together in operative position on the cylindrical portion 2. After longitudinal insertion through the recess 12, the pliable members 14 are bent laterally at the ends 15 thereof.

While I have shown and described a particular form of my invention, changes may

be effected therein without departing from the spirit and scope thereof, as set forth in the appended claims.

I claim as my invention:

- 5 1. An insulator comprising a dielectric member including a body portion having a cylindrical portion projecting therefrom and a portion projecting laterally from adjacent to the outer end of said cylindrical portion,
  - 10 and a composite ring structure including a divided inner ring surrounding said cylindrical portion, an outer ring member constituting a single integral element adapted to pass over said projection and to closely fit in position around said divided inner ring, and a pliable member extending longitudinally between said rings and bent laterally at its ends for holding the rings together.
  - 15 2. An insulator comprising a dielectric member including a body portion having a cylindrical portion projecting therefrom and an annular laterally-projecting flange adjacent to the outer end of said cylindrical portion, and a composite ring structure including a divided inner ring surrounding said cylindrical portion and having an outer diameter slightly greater than the diameter of
  - 20
  - 25
- said flange and an outer ring member constituting a single integral element adapted to pass over said flange and to fit in position around said inner ring, one of said rings having a longitudinal recess therein to provide an opening between said rings, and a pliable member extending through said opening and bent laterally at its ends to hold said rings together.
3. An insulator comprising a dielectric member including a body portion having a portion projecting therefrom and a portion projecting laterally from said projecting portion, and a composite structure including a divided inner ring element surrounding said first projecting portion, an outer element having a single integral ring portion adapted to pass over said lateral projection and to closely fit in position around said divided inner ring element, and a member extending longitudinally between said rings and having laterally extending portions for holding the rings together.

In testimony whereof I have hereunto subscribed my name this 17th day of October, 1925.

FRANZ REITER.
